UNITED STATES PATENT OFFICE.

ROBERT M. DE VIGNIER, OF BELLEFONTE, DELAWARE, ASSIGNOR, BY MESNE ASSIGNMENTS, TO NATIONAL VULCANIZED FIBRE CO., OF WILMINGTON, DELAWARE, A CORPORATION OF DELAWARE.

MANDREL EXTRACTOR.

Application filed February 24, 1922. Serial No. 539,052.

To all whom it may concern:

Be it known that I, ROBERT M. DE VIGNIER, a citizen of the United States, and a resident of Bellefonte, county of New Castle, State of Delaware, have invented certain new and useful Improvements in Mandrel Extractors, of which the following is a specification.

Some of the objects of the present invention are to provide a power actuated device for withdrawing mandrels from formed fibre tubes or tubes of other material; to provide means for increasing the production of fibre or other tubes which are formed by employing mandrels; to provide a mandrel extracting mechanism whereby a mandrel can be quickly withdrawn from a tube on the mandrel without breaking, bending, crimping or otherwise injuring the tube; and to provide other improvements as will hereinafter appear.

In the accompanying drawings, Fig. 1 represents an end elevation of a mandrel extracting machine embodying one form of the present invention; Fig. 2 represents a side elevation of the same; Fig. 3 represents a detail in front elevation of one form of mandrel engaging clamp employed; Fig. 4 represents a side elevation of the clamp shown in Fig. 3; Fig. 5 represents a section on line 5—5 of Fig. 1; Fig. 6 represents a detail of the jaws of the clamping means; Fig. 7 represents a section on line 7—7 of Fig. 1; Fig. 8 represents an enlarged detail in elevation of the mounting for the spring valve closing means in conjunction with the pressure fluid pipes; and Fig. 9 is a plan of the same.

Referring to the drawings, one form of the present invention consists of a head 10, here shown as suspended by posts 11, such as standard pipe lengths, from a channel bar 12 or other suitable member, the ends of which are respectively fast to angles 13 rigidly carried by fixed beams 14 or the like. Suitable stays 15 are provided between the beams 14 and the posts 11 to serve as braces to prevent lateral displacement of the suspended parts.

For permitting a mandrel 16 to pass through the head 10 and thus be drawn out of a tube 17, which has been formed upon the mandrel 16, the head 10 is provided with a substantially centrally disposed

opening 18, the diameter of which is greater than the diameter of the mandrel 16 to be withdrawn, but less than the diameter of the tube 17 carried by that mandrel. In this connection it should be noted that the head 10 is suspended a distance from the floor line sufficient to allow the usual length mandrel to be placed in position beneath it so that one end of the mandrel can be readily inserted through the opening 18.

In order to grip the end of the mandrel which protrudes through the head 10, a clamping device is provided consisting, in the present instance, of two jaws 20 and 21 having juxtaposed gripping faces 22 which are arranged to be moved towards or away from each other while maintaining a substantially parallel relation. This operation is accomplished by a lazy-tong construction comprising jaw links 24 and 25 having a common pivot 26 and connected respectively by pivot studs 27, 28 and 30, 31 to the jaws 20 and 21. The jaw links 24 are connected by a pivot stud 32 to two links 33, and the jaw links 25 are connected by a pivot stud 34 to two links 35. The links 33 and 35 have a common pivot stud 36 connecting all to a lug 37 fixedly secured to a rod 38. Thus, by moving the rod 38 in one direction the lazy-tong structure will operate to open the jaws 20 and 21, and if moved in the opposite direction will operate to close the jaws.

The pivot studs 28 and 31 ride respectively in slots 40 and 41, the former extending longitudinally of the jaws 20, and the latter being similarly arranged in the jaws 21. This arrangement assures free movement of the parts without binding and maintains the proper relation of the jaws.

For the purpose of operating the jaws 20 and 21, and transmitting power sufficient to withdraw a mandrel from its tube, the rod 38 in the present construction forms the piston rod of a piston (not shown) which is arranged to be reciprocated within a cylinder 42 which forms a prime mover of the single acting type. The cylinder 42 is rigidly suspended from the bar 12 with the piston rod 38 alined with the opening 18 and receives pressure fluid by way of a supply pipe 43 through the action of any suitable valve controlled by a lever 44. Normally, the valve maintains the cylinder 42 in

connection with an exhaust pipe 45 so that the jaws 20 and 21 are open but when the lever 44 is rotated in a clockwise direction the exhaust pipe is cut off and pressure fluid is admitted to the cylinder 42 from the pipe 43.

As a means for actuating the prime mover when the clamping jaws have been manually placed in position upon the end of a mandrel, the lever 44 is connected, for example, to a foot treadle 46 by a cable 47 or other suitable means, so that depression of the treadle 46 causes pressure fluid to enter the cylinder 42 and shift the rod 38 in the required manner.

For returning the lever 44 to its normal position for exhausting the cylinder 42 after a working stroke, a spring 50 is provided which extends from the lever 44 to an eye-bolt 51 which serves to clamp two plates 52 to the pipes 43 and 45. These plates 52 may be connected to any fixed part but the aforesaid pipes form a convenient support upon which the plates can be adjusted to maintain the proper tension upon the spring 50.

In the operation of the machine, the head 10 and its supporting adjuncts are located at a convenient place with respect to the delivery end of a tube forming machine so that as each mandrel with the formed tube is received it can be transferred to the extracting device without loss of time. The operator passes one end of the mandrel 16 through the opening 18 to bring that end of the tube 17 into abutting relation with the head 10, and then brings the clamping device into position with the jaws 20 and 21 at opposite sides of the mandrel. The foot treadle 46 is then pressed to cause the cable 47 to turn the valve lever 44 to admit pressure fluid from the supply pipe 43 to the lower end of the cylinder 42. This causes the rod 38 to move upwardly, as seen in Figs. 1 and 2, and this movement acting through the lazy-tong structure causes the jaws 20 and 21 to close upon the mandrel so that as the rod movement is continued the mandrel is withdrawn from the tube. As soon as the mandrel is removed the treadle 46 is released, whereupon the spring 50 returns it to normal position and simultaneously shifts the lever 44 to cut off the pressure fluid supply and allow the cylinder 42 to exhaust ready for the next mandrel removing operation. The tube and extracted mandrel are at once removed from the machine, and the operation being repeated with the next tube-fitted mandrel. In this way, mandrels are acted upon by the machine in succession and the operation becomes substantially a continuous one as mandrel after mandrel is delivered for extraction from its tube.

It will now be apparent that a complete

unitary structure has been devised for effectively extracting mandrels from tubes in a minimum of time and without damage to the tube from which the mandrel is removed. Furthermore, the machine requires but one operator, whereas methods heretofore employed for the removal of mandrels require at least two workmen to handle, and force out the mandrel by primitive manual means.

While but a single form is shown in which this invention may be embodied, it is to be understood that the invention is not limited to any specific construction, but might be applied in various forms without departing from the spirit of the invention or the scope of the appended claims.

Having thus described my invention, I claim:

1. In a mandrel extracting machine, the combination of a head having an opening therein to receive an end of a mandrel having a tube thereon, means to support said head, a jaw mechanism arranged to receive said mandrel end, means for simultaneously causing said jaw mechanism to grip said mandrel and to move said mandrel axially, and means to prevent said tube moving in the same direction.

2. In a mandrel extracting machine, the combination of a head having an opening therein to receive an end of a mandrel having a tube thereon, means to support said head, a jaw mechanism arranged to receive said mandrel end, means including a pressure actuated prime mover for simultaneously causing said jaw mechanism to grip said mandrel and to move said mandrel axially, and means to prevent said tube moving in the same direction.

3. In a mandrel extracting machine, the combination of a head having an opening therein to receive an end of a mandrel having a tube thereon, said opening having a diameter less than the outside diameter of said tube, means to rigidly support said head, a jaw mechanism arranged to receive said mandrel end, and power means for causing said jaw mechanism to grip said mandrel and extract said mandrel from said tube.

4. In a mandrel extracting machine, the combination of a head having an opening therein to receive an end of a mandrel having a tube thereon, said opening having a diameter less than the outside diameter of said tube, means to rigidly support said head, a jaw mechanism arranged to receive said mandrel end, and power means for causing said jaw mechanism to grip said mandrel and for causing said mechanism to move in one direction to extract said mandrel from said tube.

5. In a mandrel extracting machine, the combination of a head having an opening

therein to receive an end of a mandrel having a tube thereon, said opening having a diameter less than the outside diameter of said tube, means to rigidly support said head, a jaw mechanism arranged to receive said mandrel end, power means for causing said jaw mechanism to grip said mandrel and for causing said mechanism to move in one direction to extract said mandrel from said tube, and means for moving said mechanism in the opposite direction to open said jaws.

6. In a mandrel extracting machine, the combination of a head having an opening therethrough to pass a mandrel but to prevent the passage of a tube on said mandrel, means to rigidly support said head, a clamping device including a lazy-tong structure for engaging said mandrel, and means for actuating said structure to cause said clamping device to grip said mandrel and to move said device in a direction to extract said mandrel.

7. In a mandrel extracting machine, the combination of a head having an opening therethrough to pass a mandrel but to prevent the passage of a tube on said mandrel, means to rigidly support said head, a clamping device including a lazy-tong structure for engaging said mandrel, and manually controlled means for actuating said structure to cause said clamping device to grip

said mandrel and to move said device in a direction to extract said mandrel.

8. In a mandrel extracting machine, the combination of a head having an opening therethrough to pass a mandrel but to prevent the passage of a tube on said mandrel, means to rigidly support said head, a clamping device including a lazy-tong structure for engaging said mandrel, and means including a treadle for actuating said structure to cause said clamping device to grip said mandrel and to move said device in a direction to extract said mandrel.

9. In a mandrel extracting machine, the combination of a head having an opening therethrough to pass a mandrel but to prevent the passage of a tube on said mandrel, means to rigidly support said head, a clamping device including a lazy-tong structure for engaging said mandrel, means including a treadle for actuating said structure to cause said clamping device to grip said mandrel and to move said device in a direction to extract said mandrel, and spring means for returning said structure and treadle means to normal condition.

Signed at Wilmington, in the county of New Castle, and State of Delaware, this 18th day of February, 1922.

ROBERT M. DE VIGNIER.
